UNITED STATES PATENT OFFICE.

ARTHUR J. DAANE, OF CHICAGO, ILLINOIS, ASSIGNOR TO THE ACME PRINTING APPLIANCE CO., OF CHICAGO, ILLINOIS.

INK-DISTRIBUTING ROLLER.

Application filed March 9, 1925. Serial No. 13,941.

The invention relates to improvements in ink distributing rollers or what is generally known in the printing art as a vibrator which cooperates with the inking rollers of the press to distribute the ink upon them, so that all portions of the type will be properly inked, such as shown and described in my application dated October 13th, 1921, Serial No. 507,487 patented April 7, 1925, 10 Pat. No. 1,533,063, of which this application is a continuation in part.

The particular structure forming the basis of the application relates to a means whereby this distributing roller or vibrator may be readily attached relatively to the press or to a part of the press, the construction also permitting the distributing roller to be readily detached from the press to allow it to be cleaned when this is found necessary.

It is an object to provide a construction capable of performing the above function which is adapted to permit of its association and disconnection with respect to the press without the aid of any tools to accomplish its connection and removal; yet will be securely held with respect to the press without fear of its becoming accidentally disconnected.

In addition it is an object of the invention to provide a construction which will adapt itself to and cooperate with various surfaces over which the inking rollers pass during their travel relatively to the type and source of ink supply, and which will at all times maintain a close contact between the inking rolls and distributing roller or vibrator.

In addition it is an object to provide an adjustment whereby the proper tension will at all times be maintained between the various parts which cooperate with each other to accomplish the desired end. The structure employed is particularly adapted to be associated with a part of the inking roll saddle in which the ends of the inking roll shafts are journaled, and which in some printing press structures are carried by a swinging frame which travels across the plane of the type and ink platen. The structure whereby the association and disconnection of the distributing roller and the inking rollers is accomplished is such that it is capable of association with pins or projections which extend laterally in opposite directions from the saddles, the device being attached

by being passed over the ends of said pins or projections into a position in which said device will be held against accidental removal from the saddle and the ink distributing rollers between which the vibrator roller is arranged. As before stated, the structure is provided with a means for maintaining the distributing roller against the inking rollers. This structure also provides a means for holding the means whereby the distributing rollers are secured to the saddle in contact with the saddle and thereby prevents their accidental separation. A variable tension device is associated with this structure, so that the inking roller may be adjusted to suit various contingencies which may be present or may arise.

The embodiment of the invention illustrated is capable of being extended transversely of the axis of the roller to effect a connection and disconnection of the distributing roller, and may also employ a resilient structure to compensate for the various surfaces which the inking rollers traverse. The members whereby the distributing roller is held with relation to the inking rollers is designed to cooperate with a pin or projection which is part of the saddle of the press one of which is provided to afford a handle or finger piece to manually move the swinging frame which carries the inking rollers. The invention will be explained in detail in conjunction with the accompanying drawings, it being obvious that other arrangements may be resorted to without departing from the spirit of the appended claims forming a part hereof.

Referring to the drawings—

Figure 1 is a side view of a portion of a printing press having the invention applied thereto.

Figure 2 is a front view of a vibrator roller partially in section.

Fig. 3 is an end view of the device shown in Figure 2, and

Fig. 4 is a side view of one of the brackets shown in Figure 2 partially in section.

The invention will be explained in conjunction with a printing press having an oscillating frame which carries inking rollers which traverse the type and the platen of the press. A press of this character is usually provided with what are termed saddles which engage the opposite ends of the inking roller shafts and are carried

by the oscillating frame. These saddles are as before stated, arranged at the opposite ends of inking rollers 10 and 11, and are respectively designated 12 and 13. The devices for removably attaching the distributing roller 14 to these saddles 12 and 13 are respectively designated 15 and 16. These devices are respectively designed to cooperate or be attached to pins 17 and 18 which are part of the usual saddle structure one thereof providing a means to permit the inking rollers and frame to be moved manually when this is desired or found necessary. These devices 15 and 16 are each secured to the opposite ends of the shaft 19 upon which the distributing roller is mounted for reciprocation and permit the shaft 19 and the roller 14 which it carries to be moved relatively to the saddles and relatively to certain other parts entering into the construction of the devices 15 and 16. The devices 15 and 16 are formed to produce the vertical portion 20 and the horizontal portion 21 and as these devices correspond with each other an explanation of the construction and operation of one will suffice for an understanding of both.

The vertical portion 20 is slotted as indicated at 22 to receive an end of the shaft 19 and is further formed to produce an opening 23 which is provided to cooperate with the pins or projections 17 and 18, the slot 22 permitting the shaft to reciprocate relatively to the devices 15 and 16 and certain parts of the printing press structure. Vertically arranged spring pressed plungers 24 are secured to the ends of the shaft adjacent the vertical portion 20 and extend upwardly through an aperture 25 in the horizontal portion 21 and into a housing 26 which is carried by the horizontal portion 21. A spring 27 is provided and arranged in the housing and reacts between a shoulder on the pin and the end of the housing. This structure maintains the shaft 19 and the roller 14 in position against the inking rollers, yet permits the distributing roller to move with relation to the bracket. The housing is in threaded engagement with the horizontal portion of the bracket and is provided with a thumb or lock nut 28 to maintain the housing in its adjusted position.

The opening 23 is preferably formed to resemble a key hole slot in which one part is of a greater dimension than another part thereof. This construction is employed to allow the brackets 15 and 16 to be passed over the ends of the pins 17 and 18 and then moved transversely to the pins into engagement with a recess or reduced part formed in one or both of said pins.

These pins may both be of the same construction or may be of a relatively different construction. In the arrangement illustrated the pin or projection 18 is of an elongated

character having an enlargement 18' whereas the pin 17 is formed to produce a head 29 and a reduced part 30, which will thus provide a shoulder to maintain the vibrator roller and the brackets against endwise movement relative to the pins when the device is associated with and arranged in the reduced portion of said pin and will allow said brackets and their associated devices to pivot upon said pins during the operation of the press.

In applying the device one of the brackets such as 16 is passed over the end of the pin 18 and depressed until the enlarged portion 23 of the opening therein is opposite the enlargement 18' of the pin 18. The bracket is then moved endwise toward the other pin 17 until the bracket 15 is located beyond said last mentioned pin. The bracket 15 is then depressed until the enlarged portion of the opening 23 is opposite the head 29 of said pin 17. The structure is then moved outwardly relatively to the pin 18 until the bracket 15 is arranged opposite the reduced part 30 of the pin 17, release of this bracket permitting the reduced portion 23' of the opening in this bracket to engage the reduced part 30 of the pin 17. This locates the bracket 15 and its associated elements so that it is held against endwise movement relatively to the pin 17, the bracket 16 being simultaneously moved beyond and adjacent the enlargement 18' of the pin 18, which thus allows the reduced part of the opening therein to engage the smaller portion of this pin which thus holds the brackets against any endwise movement relatively to the pins 17 and 18. To release the roller and said brackets the brackets 15 and 16 are depressed against the action of the springs 27 transversely of the vibrator roller until the enlarged portion of the openings 23 are arranged opposite the enlarged parts of the pins. This allows the entire structure to be moved outwardly relatively to the pin 17, releasing this end of the vibrator, allowing the opposite end of said vibrator to be moved outwardly relatively to the pin 18 and be released therefrom.

From the foregoing description it is manifest that a simple and inexpensive arrangement is provided whereby a vibrating roller may be detachably held with relation to a press and held against accidental removal from the press when said press is operated.

Having thus described the invention what I claim and desire to cover by Letters Patent is:

1. In a device of the class described the combination of a roller having means for attaching said roller to a printing press, said means including a member arranged transversely of the axis of the roller and having an opening therein to permit said member to be passed over an end and transversely of an

element of the press which element has a shoulder with which the transverse member may engage and prevent endwise movement of the distributing roller when associated with said press.

2. In a device of the class described the combination of a roller having means for attaching said roller to a printing press, said means including a member arranged transversely of the axis of the roller and having a key hole shaped opening therein to permit said member to be passed over an end and transversely of an element of the press which element has a shoulder with which the transverse member may engage and prevent endwise movement of the distributing roller when associated with said press.

3. In a device of the class described the combination of a roller having means for attaching said roller to a printing press, said means including a member arranged and movable transversely of the axis of the roller and having an opening therein to permit said member to be passed over an end and transversely of an element of the press which element has a shoulder with which the transverse member may engage and prevent endwise movement of the distributing roller when associated with said press.

4. In a device of the class described the combination of a roller having means for attaching said roller to a printing press, said means including a member arranged and movable transversely of the axis of the roller and having a key hole shaped opening therein to permit said member to be passed over an end and transversely of an element of the press which element has a shoulder with which the transverse member may engage and prevent endwise movement of the distributing roller when associated with said press.

5. In a device of the class described the combination of a roller having means for attaching said roller to a printing press, said means including a resiliently mounted member arranged transversely of the axis of the roller and having an opening therein to permit said member to be passed over an end and transversely of an element of the press which element has a shoulder with which the transverse member may engage and prevent endwise movement of the distributing roller when associated with said press.

6. In a device of the class described the combination of a roller having means for attaching said roller to a printing press, said means including a resiliently mounted member arranged transversely of the axis of the roller and having a key hole shaped opening therein to permit said member to be passed over an end and transversely of an element of the press which element has a shoulder with which the transverse member may engage and prevent endwise movement of the distributing roller when associated with said press.

distributing roller when associated with said press.

7. In a device of the class described the combination of a roller having means for attaching said roller to a printing press, said means including a member arranged transversely of the axis of the roller, a guideway provided in said member in which an end of the roller is mounted, said member having an opening therein to permit said member to be passed over an end and transversely of a projection which is an element of the press to secure said member to said element.

8. In a device of the class described the combination of a roller having means for attaching said roller to a printing press, said means including a member arranged and movable transversely of the axis of the roller, a guideway provided in said member in which an end of the roller is mounted, said member having an opening therein to permit said member to be passed over an end and transversely of a projection which is an element of the press to secure said member to said element.

9. In a device of the class described the combination of a roller having means for attaching said roller to a printing press, said means including a member arranged transversely of the axis of the roller, a guideway provided in said member in which an end of said roller is mounted, yieldable means for moving said roller toward an end of the guideway, said member being provided with means for the reception of a shouldered projection which is part of said press and said means permitting the member to be moved endwise of the projection beyond the shoulder of the projection and laterally relatively to the projection to arrange said member so that said member may engage the shoulder and prevent endwise movement of said member relatively to the projection.

10. In a device of the class described the combination of an ink distributing roller having means for attaching said roller to an ink distributing roller frame having pins projecting in opposite directions from said frame, one of said pins having a head and a reduced portion, said means including members provided at the opposite ends of the distributing roller which extend laterally from the distributing roller and are provided with an opening whereby said members may be passed over the ends of said pins and be arranged with respect to the head and reduced portion of said pin to prevent endwise movement of said members relatively to said inking roller frames.

11. In a device of the class described the combination of an ink distributing roller having means for attaching said roller to an ink distributing roller frame having pins projecting in opposite directions from said frame, one of said pins having a head and

a reduced portion, said means including members provided at the opposite ends of the distributing roller which extend laterally from the inking roller and are provided with an opening whereby said members may be passed over the ends of said pins and be arranged with respect to the head and reduced portion of said pin to prevent endwise movement of said members relatively to said inking roller frames, said members being provided with means permitting the inking roller to move lengthwise of said members when associated with said press.

12. In a device of the class described the combination of an ink distributing roller having means for attaching said roller to an ink distributing roller frame having pins projecting in opposite directions from said frame, one of said pins having a head and a reduced portion, said means including members provided at the opposite ends of the distributing roller which extend laterally from the inking roller and are provided with an opening whereby said members may be passed over the ends of said pins and be arranged with respect to the head and reduced portion of said pin to prevent endwise movement of said members relatively to said inking roller frames, said members being provided with means permitting the inking roller to move lengthwise of said members when associated with said press and resilient means for maintaining said members in associated relation with said pins.

13. In a device of the class described the combination of a vibrator roller having means for attaching said roller to the frames to which the ink distributing rollers of a press are attached, said frames having pins which extend outwardly therefrom, one of said pins having a head and a reduced portion the other pin having a reduced portion and an enlargement forming a shoulder,

der, said means of the vibrator roller including members provided at the opposite ends of the distributing roller having means permitting one of said members to be passed over the enlargement of the second mentioned pin to thereby arrange the other member beyond the end of the pin having the head, both of said members being movable longitudinally of said pins to thereby allow one of said members to be passed over the end of the pin having the head into engagement with the reduced portion of said pin and the other member to be arranged adjacent the side of the enlargement and in engagement with the reduced portion of the pin having said enlargement.

14. In a device of the class described the combination of a vibrator roller having means for attaching said roller to the frames to which the ink distributing roller of a press is attached, said frames having pins which extend outwardly therefrom, one of said pins having a head and a reduced portion the other pin having a reduced portion and an enlargement forming a shoulder, said means of the vibrator roller including members provided at the opposite ends of the distributing roller having an opening permitting one of said members to be passed over the enlargement of the second mentioned pin to thereby arrange the other member beyond the end of the pin having the head, both of said members being movable longitudinally of said pins to thereby allow one of said members to be passed over the end of the pin having the head into engagement with the reduced portion of said pin and the other member to be arranged adjacent the side of the enlargement and in engagement with the reduced portion of the pin having said enlargement.

In witness whereof, I hereunto subscribe my name this 26th day of February A. D., 1925.

ARTHUR J. DAANE.
